UNITED STATES PATENT OFFICE

2,441,777

RECEIVER FOR USED BLADES

Nicholas Testi, Boston, Mass., assignor to Gillette Safety Razor Company, Boston, Mass., a corporation of Delaware.

Application April 20, 1945, Serial No. 589,283

6 Claims. (Cl. 206—16)

1

This invention consists in a novel receiver for used safety razor blades and a new combination of blade magazine and receiver.

The problem of disposing of used safety razor blades has always been a troublesome one and built-in receivers are now available in some locations where the user may deposit used blades by hand. The public is now being offered a type of safety razor and blade magazine so constructed and arranged that the used blade is mechanically removed from the safety razor. Handling of used blades is thus reduced to the steps of taking the used blade from some sort of a mechanical gripper which has removed it from the razor and then disposing of the blade as has been done heretofore. The object of the present invention is to provide a container to which the user may present a used blade while still held by a mechanical gripping device, or by a gripping part of a magazine which has withdrawn the blade from the safety razor, and which will then take control of the used blade without requiring the user even to touch the blade.

Going more into detail, the receiver of my invention is constructed and arranged to co-operate with a magazine having spring-gripping fingers for engaging a used blade in the safety razor, withdrawing the blade from the razor and presenting it to the user for disposal. The blade-gripping instrumentalities are resilient or spring-controlled and so shaped as to impart an impulse of translation to the used blade at the instant of its disengagement from the gripping device. The receiver of my invention comprises an enclosure of suitable size, having an inlet slot and an internal blade-engaging projection arranged to retain a perforated blade when once it has been inserted through the slot. Having presented one end of the blade through the inlet slot without removing it from the gripping device, the blade is hooked against withdrawal and held positively while the gripping device is retracted. The used blade is thus drawn frictionally out of the gripping device and at the instant of disengagement the latter imparts a forward or inward impulse to the blade so that the blade is shot or jerked suddenly into the receiver and safely enclosed out of harm's way.

Preferably and as herein shown, the blade-engaging projection within the receiver has an inwardly and downwardly inclined edge surface

which leads the blade downwardly, depositing it in stacked formation with other blades similarly received. This feature of construction contributes to the provision of a receiver of substantial capacity since by stacking the used blades they are arranged in the manner most economical of space.

These and other features of the invention will be best understood and appreciated from the following description of a preferred embodiment thereof, selected for purposes of illustration and shown in the accompanying drawings in which:

Fig. 1 is a view in perspective of the receiver showing a blade being presented thereto by the gripping device of a blade magazine.

Fig. 2 is a fragmentary view in perspective of the gripping device showing one end of a blade; and

Fig. 3 is a view in longitudinal section corresponding to Fig. 1.

The receiver may be constructed of wood or light metal or molded resinous material and, as herein shown, comprises two parts, a main rectangular body portion 10 having a flanged base 11 and a separate bottom 12, which is designed to be sprung or forced into undercut grooves formed in the flanges of the base 11. The body 10 includes a flat cover 13 and in its front wall, just beneath the cover, is formed a horizontal inlet slot 14 of sufficient width to receive a used blade with clearance.

The base 12 is provided with an upwardly projecting plate 15, having an inwardly and upwardly sloping upper edge which terminates in a projecting hook 16 standing just below the inner face of the cover 12, opposite to the inlet slot 14 and at substantially the same level. At its base the projecting plate 15 is substantially longer than the width of the blade slot and being herein shown as approximately the full length of the blade slot. Its forward edge is substantially vertical while its rear edge slopes downwardly and rearwardly from the hook 16. A slotted blade presented endwise through the inlet slot 14 and pushed in until the end of its slot registers with the hook 16 will be guided inwardly by the rear sloping edge of the plate 15 as the blade drops by gravity inside the receiver and all blades so presented are held stacked in vertically superposed relation by the plate 15.

50 The receiver herein shown is adapted to handle

double-edged blades of commercial type. As shown in Fig. 2, each of these blades 17 is provided with a longitudinal medial slot 18, having local enlargements of various contours. The blade also has reentrant corner notches forming elongated unsharpened end portions 19 at both ends of the blade. The plate 15 is of such width and length as to receive with clearance the slot 18 of these blades 17.

The receiver herein described may be employed advantageously in connection with any mechanical blade-gripping device; for example, with that of the blade magazine of my prior Letters Patent No. 2,397,890, dated April 2, 1946, and when so employed the blade is shot or snatched into the receiver in an unexpected manner. The magazine includes in its organization an outer rectangular casing 20 upon which is movably mounted a feed slide 21 carrying a double-ended blade-gripping device. This is formed a spring sheet metal or other resilient material and comprises at each side of the feed slide 21 a downturned centrally disposed finger 22, and upturned fingers 23.

The magazine has the double function of presenting a fresh unused blade to a safety razor and of gripping and withdrawing the used blade. The details of the blade-removing operation are not of interest here beyond the fact that at the conclusion of the blade-feeding step the gripping fingers 22 and 23 are forced over the end of the blade, the central finger 22 being sprung slightly downwardly and the side fingers 23 being sprung slightly upwardly as indicated in Fig. 2. The user may, of course remove the used blade from the fingers 22-23 and place it by hand in the receiver. If, however, the user presents the magazine to the receiver in the condition shown in Fig. 3, he will have no occasion at all to touch the blade with his fingers and so may completely avoid danger of cutting himself. The blade 17 enters the inlet slot, its end passes over the hook 16 and it is positively retained against being retracted. If now the magazine is retracted, the fingers 22-23 are frictionally withdrawn from contact with the blade 17 and, as a last step of this withdrawal, the central finger 22 will snap upwardly and the two side fingers 23 will snap downwardly, the result is to give the blade sharp forward impulse. This causes the blade apparently to leap inwardly into the receiver where it immediately settles itself upon the plate 15 and is guided inwardly into alignment with the stack of blades being built up in stacked formation upon the plate 15. The removal of the blade in this manner from the gripping fingers of the magazine completely frees the magazine leaving the used blade safely contained out of harm's way.

It will be understood that the outer ends of the blade-gripping fingers 22 and 23 are beveled or curved in opposite directions at their extreme ends and that movement of the blade into the receiver is caused by the reaction of the curved or beveled surfaces of these fingers against the rear edge of the end portion 19 of the blade at the instant of disengagement. When the blade is inserted through the inlet slot 14, its end portion rides upwardly upon the rearwardly and upwardly sloping edge of the plate 15. It is confined in this movement by the inner surface of the cover 13 and in this sense the inner face of the cover and the upper edge of the plate 15 constitutes converging guide surfaces which control the movement of the entering blade until the hook 78

16 passes into the slot 18 of the blade. The blade is now positively held against retraction so that the magazine may be removed, leaving the blade where it is. When the gripping fingers 22 and 23 finally slip off the rear edge of the blade, the latter leaps forwardly in the manner already explained, passing entirely through the inlet slot 14, and when this occurs the blade falls to the bottom of the receiver, being guided inwardly and downwardly in this movement by the inclined inner edge of the plate 15 and being prevented by the plate from twisting. A blade 17 is indicated in dotted lines in the position it occupies when it has just cleared the inlet slot 14. Other blades are shown in stacked formation to the base of the plate 15.

Having thus disclosed my invention and described in detail an illustrative embodiment thereof, I claim as new and desire to secure by Letters Patent:

1. A receiver for used blades, comprising a box-like enclosure having a flat top and a vertical wall with a horizontal blade inlet slot in its upper portion, and a blade-engaging plate of substantial length disposed transversely to the slot, located within the enclosure having a hooked and standing opposite the inlet slot and adjacent to the top of the enclosure.

2. A receiver for used blades, comprising a box-like enclosure having a flat top and a vertical wall with a transverse blade inlet slot adjacent the top of the vertical wall, a bottom detachably retained in the enclosure, and an upstanding plate secured to the medial part of said bottom and extending in edgewise relation into proximity to said slot and having a hooked end directed away from the slot, whereby a slotted blade inserted endwise through the slot is impaled upon said upstanding plate and prevented from twisting thereby.

3. A receiver for used blades, comprising a box-like enclosure having a flat top and a vertical wall with a transverse blade inlet slot therein, a bottom detachably retained in the enclosure, and an upstanding plate secured to said bottom and having a top edge extending inwardly and upwardly with respect to the inlet slot and cooperating with the top of the enclosure to guide a blade into empaling position when the blade is inserted through the slot, the said edge terminating at its inner end in a retaining hook.

4. A receiver for used slotted blades, comprising an enclosure having a transverse inlet slot, and a blade-engaging plate located within the enclosure and having an upper edge inclined inwardly and upwardly with reference to said inlet slot converging toward the top of the enclosure and constituting therewith converging guiding surfaces for controlling the path of a blade inserted through the inlet slot.

5. A receiver for used blades, comprising a rectangular enclosure, having a flat top and an upright wall with a transverse blade inlet slot in its upper portion, and an upwardly extending blade-entering projection located within the enclosure and having a hooked end at substantially the same level as the inlet slot which is directed away from the slot and adjacent to the top of the enclosure.

6. A receiver for used razor blades of the slotted type, comprising an enclosure having an upright wall with an inlet opening near its upper edge, and a blade-engaging device projecting upwardly from the bottom of the enclosure and terminating in a hooked end adjacent to its inlet opening in position to engage and positively retain each

successive blade presented endwise through said opening, and having an inwardly and downwardly sloping edge acting to guide the blade inwardly and position it parallel to the bottom in the receiver, said hooked end and sloping edge being directed away from the slot.
